UNITED STATES PATENT OFFICE.

PAUL A. GINTER, OF TOLEDO, OHIO, ASSIGNOR TO THE AMERICAN BOTTLE COMPANY, OF TOLEDO, OHIO, A CORPORATION OF OHIO.

DESIGN FOR A BOTTLE.

Application filed February 28, 1925. Serial No. 12,511. Term of patent 14 years.

To all whom it may concern:

Be it known that I, PAUL A. GINTER, a citizen of the United States, residing at Toledo, in the county of Lucas and State of Ohio, have invented a new, original, and ornamental Design for Bottles, of which the following is a specification.

The figure is an elevation view of a bottle, showing my new design. The design of the bottle as viewed from the opposite side is identical with that shown in the drawing.

I claim:

The ornamental design for a bottle, substantially as shown.

Signed at Toledo, in the county of Lucas and State of Ohio, this 25th day of February, 1925.

PAUL A. GINTER.
